UNITED STATES PATENT OFFICE.

JOHN JONES TURNER AND JAMES ALBERT DOWLER, OF LAHARPE,
KANSAS.

MOLDING-MACHINE.

SPECIFICATION forming part of Letters Patent No. 752,484, dated February 16, 1904.

Application filed July 15, 1903. Serial No. 185,646. (No model.)

To all whom it may concern:

Be it known that we, JOHN JONES TURNER and JAMES ALBERT DOWLER, both citizens of the United States, and residents of Laharpe, 5 in the county of Allen and State of Kansas, have invented a new and Improved Molding-Machine, of which the following is a full, clear, and exact description.

The invention relates to molding-machines 10 for forming vessels of plastic material, such as condensers made of clay and used in retorts employed in zinc-smelters.

The object of the invention is to provide a new and improved molding-machine which is 15 simple and durable in construction, easily manipulated, and arranged to allow of forming the vessels of uniform size and shape without requiring the employment of skilled labor.

The invention consists of novel features and 20 parts and combinations of the same, as will be more fully described hereinafter and then pointed out in the claims.

A practical embodiment of the invention is 25 represented in the accompanying drawings, forming a part of this specification, in which similar characters of reference indicate corresponding parts in all the views.

Figure 1 is a sectional side elevation of the improvement. Fig. 2 is a reduced sectional 30 plan view of the same on the line 2 2 of Fig. 1. Fig. 3 is a plan view of one of the top plates of the carrier. Fig. 4 is a similar view of a bottom plate of the carrier. Fig. 5 is a cross-section showing the attachment of the 35 carrier-plates on the carrier-beam. Fig. 6 is an enlarged sectional plan view of the core and cut-off knife for cutting off the surplus material on the top of the mold. Fig. 7 is an enlarged sectional plan view of the stem of 40 the core and its driving gear-wheel. Fig. 8 is a side elevation of one of the molds in an open position, and Fig. 9 is a sectional plan view of the same in a closed position.

On a suitably-constructed base A is secured 45 a hollow cylindrical standard B, on which is mounted to turn a carrier C for carrying molds D, operating, successively, in conjunction with a core E, mounted to turn and to slide in the direction of its length in and out

of a mold at the time in axial alinement with 50 the core, as hereinafter more fully described. The carrier C is preferably in the shape of an open framework supporting a top plate C' and a bottom plate C'', made in ring shape and 55 preferably in sections bolted or otherwise fastened to the radial beams of the open framework, as will be readily understood by reference to Figs. 1, 2, 3, 4, and 5. The top plate C' is provided with apertures C³, arranged in a circle for receiving the molds D, and on the 60 top of the bottom plate C'' are arranged annular retaining-flanges C⁴, likewise arranged in a circle and vertically in alinement with the apertures C³ in the top plate C'.

Each mold D is made in sections hinged 65 together, which when closed fit the apertures C³ and rest with their bottoms D' on the bottom plate C'' against the inner edges of the annular retaining-flanges C⁴, so as to hold the molds against lateral movement. The sides 70 of the mold D are provided with lugs D², extending lengthwise and fitting corresponding recesses C⁵ in the walls of the openings C³, so as to hold the molds against turning, as will be readily understood by reference to Figs. 1 75 and 3.

The bottom plate C'' is provided with apertures C⁶, concentric with the annular retaining-flanges C⁴ and adapted to receive the lower 80 end of the core E to close the apertured bottom D' of the mold, the said core being so arranged relative to the mold engaged at the time that an annular space is left between the outer surface of the core and the inner surface of the mold for forming a vessel having 85 a central opening, as will be understood by reference to Fig. 1.

The upper end of the core E is provided with a stem or shaft E', turning with and mounted to slide lengthwise in a bevel gear-wheel F, in mesh with a bevel gear-wheel F', secured on a shaft F², carrying fast and loose pulleys F³, connected by a belt with other machinery for rotating the shaft F², which by the bevel gear-wheels F and F' imparts a rotary motion to the stem E' and the core E to 95 turn the latter.

On the stem E' are secured collars E² and

E^3 , between which is arranged a sleeve G , provided with a handle G' , adapted to be taken hold of by the operator for sliding the stem E' and its core E up or down out of or into the mold D then in axial alinement with the said core.

In order to allow easy up-and-down sliding movement of the stem E' and its core E , a counterbalancing device is provided, preferably consisting of a chain G^3 , attached at one end to the upper end of the sleeve G and extending over pulleys G^3 G^4 to carry at its other end a weight G^5 , mounted to slide up and down in the hollow standard B .

As shown in Fig. 1, the sleeve G is mounted to slide in a bearing carried by an arm B' , projecting from the standard B , and the upper portion of the stem E' is mounted to slide and to turn in a suitable bearing carried by an arm B^2 , likewise projecting from the standard B .

In order to cut off the surplus material on the top of the mold D , a knife H is provided, secured to the upper end of the core E and flush at its cutting edge with the top edge of the mold, so that when the core E is in the mold and rotates then the knife H is carried around with the core, and consequently cuts off the surplus material from the top of the mold to render the vessels formed of uniform length.

In order to lock the carrier C temporarily in position at the time a mold D is in axial alinement with the core E , the lower or bottom plate C^2 is provided in its peripheral edge with notches C^7 , one for each retaining-flange C^4 , and each notch is adapted to be engaged by the upper end of an arm I , fulcrumed on a bracket I' and provided with a treadle I^2 , pressed on at its under side by a spring I^3 to hold the arm I normally in engagement with a notch C^7 .

From the peripheral edge of the top plate C' extend radial handles C^8 , adapted to be taken hold of by the operator for conveniently turning the carrier C , and with it the molds, at the time the core E is in an uppermost position—that is, out of engagement with the mold—so as to enable the operator to bring the next following mold in axial alinement with the core. Now previous to turning the carrier C the operator presses the treadle I^2 with the foot, so as to swing the arm I out of engagement with the corresponding notch C^7 to unlock the carrier, and then by the operator manipulating the handle C^8 a turning movement is given to the carrier C and its molds until the next mold comes in axial alinement with the core E . As the operator releases the treadle I^2 the arm I snaps into the next notch C^7 and again locks the carrier C in place.

In order to insure an easy rotation of the carrier C , the latter is provided at its under side with depending brackets J , in which are journaled friction-wheels J' , mounted to

travel on an annular track J^2 , secured to the floor or other support for the machine.

In order to keep the core E perfectly clean and smooth, a brush K is provided, secured on a bracket K' , depending from the arm B' , the free ends of the bristles of the brush engaging the peripheral face of the core E , so that when the latter rotates and is moved up and down by the operator out of and in the mold then the bristles of the brush K come in contact with the entire peripheral surface of the core E , thus wiping the same and keeping it in proper condition to prevent the material forming the vessel from sticking to the core. The bristles of the brush K are preferably supplied with oil or like liquid to facilitate the wiping of the core E , and for this purpose a supply-pipe L is provided having a valve L' and leading from the bottom of a tank N , containing oil or other liquid and supported on the top of the standard B .

The operation is as follows: The molds are inserted in the carrier C , and a lump or ball of clay or other material is thrown into the mold, and then the carrier C is held temporarily in a locked position by the arm I . The core E , normally in an uppermost position, is now moved downward by the operator pulling the handle G in the same direction, so that the rotating core is wiped perfectly clean by the brush K and passes into the mold D to press the lump or ball of plastic material into the space between the core and the inner wall of the mold, thus forming a tubular vessel, it being understood that the material is retained within the mold D as the lower end of the core E passes into the opening C^6 in the bottom plate C^2 . The surplus material on the top of the mold D is cut off by the knife H , carried around by the revolving core E . When the vessel has been formed, the operator pushes the handle G' upward, so as to move the still-rotating core E out of the mold, and then the operator presses the treadle I^2 to temporarily unlock the carrier C to allow the operator to turn the carrier until the next mold D is in axial alinement with the core E . The above-described operation is then repeated.

It is understood that the stem E' is splined a sufficient length to allow its up-and-down movement without disengagement from the gear-wheel F , so that a continuous rotary motion is given to the stem E' and its core E .

As shown in Figs. 1, 8, and 9, the mold D is preferably made in its lower portion in the shape of the frustum of a cone and in its upper portion cylindrical, and the core E is similarly shaped to produce a tubular vessel having its lower portion in the shape of the frustum of a cone and the upper part cylindrical, so as to allow the convenient use of the vessel as a condenser for employment in retorts of zinc-smelters.

The mold is made in hinged sections to permit of conveniently opening the mold in case the tubular vessel formed in the mold sticks to the sides thereof. In practice the mold is 5 preferably greased on the inside to reduce the sticking of the vessel to the mold to a minimum. A handle D^3 for carrying the mold about is arranged on one section of the mold and is adapted to engage a keeper D^4 on the 10 other section to lock the sections in a closed position.

Having thus described our invention, we claim as new and desire to secure by Letters Patent—

15 1. A molding-machine comprising a revolvable mold-carrier, having supports arranged in a circle and each supporting molds, a core mounted to turn and to move in the direction of its length, to pass in and out of the mold 20 in register at the time with the core, and a knife on the said core, operating over the end of the mold, to cut off the surplus material, to form articles of uniform length, as set forth.

2. A molding-machine comprising a revolvable mold-carrier, having supports arranged 25 in a circle and each supporting molds, a core mounted to turn and to move in the direction of its length, to pass in and out of the mold in register at the time with the core, and a 30 wiping device for the said core, as set forth.

3. A molding-machine comprising a revolvable mold-carrier, having supports arranged 35 in a circle and each supporting molds, a core mounted to turn and to move in the direction of its length, to pass in and out of the mold in register at the time with the core, and a fixed brush having its bristles in engagement with the side of the core, to wipe the latter clean, as set forth.

40 4. A molding-machine comprising a revolvable mold-carrier, having supports arranged in a circle and each supporting molds, a core mounted to turn and to move in the direction of its length, to pass in and out of the mold 45 in register at the time with the core, a fixed brush having its bristles in engagement with the side of the core, to wipe the latter clean, and an overhead oil-supply tank and pipe, for feeding oil onto the said bristles, as set forth.

50 5. A molding-machine comprising molds, open at the top and bottom, a revolvable mold-carrier having apertured top and bottom plates for supporting the molds and of which each bottom plate is provided with a retaining-flange for the lower ends of the molds, and a core, mounted to turn and adapted to slide in the direction of its length, to pass into and out of the mold at the time in axial alinement with the core, the bottom end of the core engaging an opening in the bottom plate of the carrier, as set forth.

60 6. A molding-machine comprising molds, open at the top and bottom, a revolvable mold-carrier having apertured top and bottom plates for supporting the molds and of which

each bottom plate is provided with a retaining-flange for the lower ends of the molds, a core, mounted to turn and adapted to slide in the direction of its length, to pass into and out of the mold at the time in axial alinement 70 with the core, the bottom end of the core engaging an opening in the bottom plate of the carrier, and handles on the carrier, for periodically turning the carrier, as set forth.

7. A molding-machine comprising molds, 75 open at the top and bottom, a revolvable mold-carrier having apertured top and bottom plates for supporting the molds and of which each bottom plate is provided with a retaining-flange for the lower ends of the molds, a core, 80 mounted to turn and adapted to slide in the direction of its length, to pass into and out of the mold at the time in axial alinement with the core, the bottom end of the core engaging an opening in the bottom plate of the carrier, 85 handles on the carrier, for periodically turning the carrier, and a manually-controlled locking device, for locking the carrier temporarily against rotation at the time a mold is in register with the core, as set forth. 90

8. A molding-machine having a mold-carrier provided with circular plates, and molds, each made in sections hinged together and having lugs and engaging recesses in the said plates, to hold the molds against rotation in 95 the plates, as set forth.

9. In a molding-machine, a mold-carrier, a core, the carrier and core having movement relatively one to the other to cause the core to enter the mold on the carrier, and a wiping device for wiping the core when it is withdrawn from the mold, as set forth.

10. In a molding-machine, a mold-carrier, a core, the carrier and core having movement relative one to the other to cause the core to 105 enter the mold on the carrier, a wiping device for wiping the core when it is withdrawn from the mold, and means for supplying a liquid to the wiping device, as set forth.

11. A molding-machine, comprising a base 110 having a hollowed standard, provided with lateral arms, a mold-carrier mounted to turn on the standard and to travel on the base, a core for entering the molds carried by the said carrier, said core having a stem mounted 115 to slide and turn in the arms of the standard, means geared with the stem of the core for rotating it, a handle secured to the stem for sliding it, a weight in the hollow standard, and a flexible connection between the weight 120 and stem of the core, as set forth.

In testimony whereof we have signed our names to this specification in the presence of two subscribing witnesses.
